(57) **CLAIM**

The ornamental design for an automobile tire, as shown and described.

DESCRIPTION

FIG. 1 is a front view of the automobile tire showing my new design;

FIG. 2 is a right-side view thereof;

FIG. 3 is a top view thereof;

FIG. 4 is a perspective view thereof;

FIG. 5 is an enlarged cross-section view thereof, taken along the line A1—A1 of FIG. 1; and,

FIG. 6 is an enlarged view thereof, of the part B1—B2 in FIG. 1.

The broken lines representing the tire side wall are for illustrative purposes only and form no part of the claimed design.
